UNITED STATES PATENT OFFICE.

HENRY C. PORTER, OF WAUKEGAN, ILLINOIS, ASSIGNOR TO PORTER BATTERY COMPANY, OF CHICAGO, ILLINOIS, A CORPORATION OF ILLINOIS.

BATTERY-PLATE.

SPECIFICATION forming part of Letters Patent No. 763,322, dated June 21, 1904.

Application filed July 14, 1902. Serial No. 116,512. (No model.)

To all whom it may concern:

Be it known that I, HENRY C. PORTER, a citizen of the United States, residing at Waukegan, in the county of Lake and State of Illinois, have invented certain new and useful Improvements in One-Piece Battery-Plates, of which the following is a specification.

My invention relates particularly to battery-plates used in secondary or storage batteries.

The object of my invention is to provide a durable, compact, inexpensive, and simple plate. These and such other objects as may appear are obtained by the device shown in the accompanying drawings, in which—

Figure 1 shows a side elevation of one of my improved plates with a portion of one side thereof broken away. Fig. 2 is a sectional view on the line 2 2 of Fig. 1 looking in the direction indicated by the arrows. Fig. 3 is a plan view. Fig. 4 is a detail showing a fractional portion of a complete plate. Fig. 5 is a sectional view on the line 5 5 of Fig. 4 looking in the direction indicated by the arrows. Fig. 6 is a perspective view of a tablet of active material. Fig. 7 is a perspective view of a plate, showing a tablet being inserted in one of the pockets of the plate. Fig. 8 is a perspective view of a completed plate.

Like letters of reference indicate the same parts in the several figures of the drawings.

In preparing my plate I first cast the plate in the form of a casing A, having a terminal a and provided with a plurality of internally-arranged ribs B, which preferably extend longitudinally of the plate and parallel with each other and which preferably are integral with both walls of the casing, thereby dividing the casing into a plurality of pockets C. In casting this casing in its preferred form it is altogether better to cast it so that it is closed on all sides except at one edge, which is left open so as to leave each of the pockets C open at one end thereof. To facilitate the closing of this open edge of the plate after the same has been properly filled with active material, I prefer providing this edge with a slight depression or slot D, extending longitudinally

thereof, although this open edge of the casing may be closed in any suitable manner—such, 50 for instance, as by “burning” to this edge of the plate a strip of metal of the requisite dimensions. So, also, if desired, the opposite ends of the pockets C may be left open, as the filling process under some conditions might be 55 interfered with by the presence of air within the closed ends of the pockets; but I do not consider such additional openings as at all essential. As very small openings will suffice for the escape of imprisoned air, such air-escape openings need not necessarily be closed as a step in the completion of the plate; but whether or not such additional openings shall be closed is a matter depending wholly upon the size thereof, as well, perhaps, as upon 60 other conditions which may arise in any given case, but which do not relate to the spirit of my invention. Indeed, as usually constructed the space included between the opposite faces of the casing A is only about one-eighth 65 of an inch wide, so that it is entirely practical and may under some conditions be deemed preferable to leave either or both ends of the pocket C open, so that the active material will have a tendency to adhere closely within the 70 pockets C and when solidified by a forming process will have little if any tendency to leave 75 the pockets C.

My improved plate is prepared as follows: Starting with the casing A, provided with the 80 pockets C, freely open at one end thereof and with or without openings at the opposite ends thereof, I fill the pockets C with suitable active material, preferably in a paste-like condition, and then, supporting the plate in any 85 suitable manner, close the freely-open ends of the pockets C in any suitable manner. In practice I prefer closing the freely-open ends of the pockets C by the use of hydrogen-burner and a small stick of lead or other suitable fusible material, which is melted by the hydrogen-burner and fills the slight groove or slot D across the open ends of the pockets C. I next perforate the sides of the casing A in any suitable manner, but preferably by running the same through a press provided with 90 95

punching devices so arranged as to punch holes E through the metal of the sides of the casing into the active material F contained in the pockets C, thereby still further compressing the already-closely packed active material in these pockets and forming tangs e, which are forced into and engage this active material. The plate is next subjected to any familiar forming process, thereby transforming the active material into a solid compound, which is solidified around the tangs e and adheres closely thereto.

It will thus be seen that I produce a one-piece battery-plate so constructed that there is practically no possibility of any loss of active material therefrom and in which the loss of contact between the metal of the plate and the active material because of contraction and expansion within the plate is reduced to a minimum and in which the active material is so confined and supported that I am enabled to dispense with in the neighborhood of three-quarters of the number of supporting-ribs as used in the ordinary battery-grid, thereby not only diminishing the cost of the plate, but also reducing the weight thereof, for although the active material is surrounded by walls of lead or lead alloy such walls are so integrally connected with each other and are so attached to the active material by virtue of the tangs, which project therefrom and are embedded in the active material which was subsequently solidified around them, that I am enabled to use a plate having very thin walls, while at the same time obtaining a plate of sufficient strength and rigidity for service condition.

Of course my invention is not confined to the precise manner of construction shown, either as to the arrangement of the ribs, the manner of closing the open end of the plate, or as to other such details, which, as a matter of shop convenience, will naturally be varied from time to time to meet varying conditions and requirements. Under some conditions it may be found convenient to mold the active material into tablets, such as the tablet F, (shown in Fig. 6 of the drawings,) of such form and dimension as to fit readily but snugly within the pockets C. This will facilitate charging the pockets with active material, and, if desired,

the tablets may then be softened by immersing the plate in a suitable fluid before or during the perforating process. Under these conditions the perforating process will have a tendency to force the softening tablets snugly into all corners of the pockets C, so as to have intimate contact with the metal of which the casing and ribs are formed.

I claim—

1. A battery - plate comprising a casing closed on all sides except on one edge, and being formed with depressions at said open edge, an active material arranged in said plate, and means adapted to coöperate with said depressions to close said plate. 60

2. A battery-plate comprising a casing having one of its edges open, partitions arranged in said casing and having one of their ends terminating at the open edge of the casing, 70 the ends of the upper and lower walls at said open edge of said casing, and the adjacent ends of the partitions being depressed, a filling of active material arranged between said partitions, and means adapted to coöperate with 75 said depressions to close said plate.

3. A battery - plate comprising a casing closed on all sides except at one edge, a series of integral partitions arranged in the said casing, a filling of active material arranged between the said partitions, and means independent of the casing proper for closing the open edge of the said casing. 80

4. The combination with the casing formed with a series of pockets one end of which is 85 open, the walls of said casing at the open ends of said pockets being formed with depressions, of a filling of active material, and means adapted to coöperate with said depressions to close said plate. 90

5. The combination with the casing having one of its sides open, partitions arranged in the said casing, at right angles to the said open side, one end of the upper and lower walls and partitions of the said casing being formed with depressed portions, and a filling of active material arranged between the said partitions. 95

HENRY C. PORTER.
